UNITED STATES PATENT OFFICE

MYRON H. RICHARDSON, OF CHICAGO, AND ALBERT E. GEBERT, OF WILMETTE, ILLINOIS, ASSIGNORS TO ADVANCE MACHINE COMPANY, OF CHICAGO, ILLINOIS, A CORPORATION OF ILLINOIS

CHECK-CONTROLLED MECHANISM

Original application filed February 4, 1927, Serial No. 165,783. Divided and this application filed July 23, 1927. Serial No. 207,876.

This application is a division of our original application Serial No. 165,783, filed February 4, 1927.

In our original application there is shown and described an improved vending machine embodying a plurality of containers mounted to revolve about a common upright axis and means are provided for arresting the containers in proper positions with respect to the 10 ejecting mechanism to be delivered by the actuation of check controlled mechanism.

The present invention, however, relates to check controlled mechanism and more specifically to the means for returning the check 15 or coin to the operator when the containers are empty.

To the attainment of these ends and the accomplishment of other new and useful objects as will appear, the invention consists in the 20 features of novelty in substantially the construction, combination and arrangement of the several parts hereinafter more fully described and claimed and shown in the accompanying drawings illustrating this invention, 25 and in which.

Figure 1 is a horizontal sectional view of a vending machine having check return mechanism constructed in accordance with the principles of this invention applied thereto, parts 30 of the machine being shown in section, parts in elevation, parts broken away and with parts omitted.

Figure 2 is a vertical sectional view as taken on line 2—2, Figure 1, and showing articles in one of the containers.

Figure 3 is an irregular horizontal sectional view taken on line 3—3, Figure 2.

Figure 4 is a detail vertical sectional view 40 taken on line 4—4, Figure 2, and with parts omitted.

Figure 5 is a detail perspective view of the lower portion of one of the containers showing a weight therein.

Figure 6 is a detail view partly in elevation, partly in section and partly broken away of the check controlled mechanism.

Referring more particularly to the drawings there is shown a plurality of containers 50 11 rotatably mounted upon a suitable struc-

ture and arranged to rotate about a common axis 12.

These containers are rotated in any suitable manner and are adapted to be arrested at predetermined points in the cycle of rotation of the container so that the articles will be discharged through a delivery chute to the customer. 55

It sometimes happens that it is attempted to actuate the mechanism when the machine is 60 empty and in that event the check deposited by the operator should not be retained in the machine at a loss to the operator.

The present invention provides means whereby the mechanism will be automatically 65 locked against operation after the machine has become empty and it is preferably accomplished through the medium of the articles themselves.

This mechanism will cause the check to be 70 returned to the operator in the event that the containers are empty.

To that end there is provided a lever 13 which is pivotally mounted intermediate its ends as at 14 to a suitable support 15, and the lever is provided with a portion 16 that is arranged adjacent the path of movement of the containers. Connected with the lever is a bar or rod 17 which is so shaped that the end 18 thereof is adapted to be projected 80 into the path of movement of the periphery of a check 19 which is carried in a check seat 20 of a check carrier 21. 75

A spring 22 is provided which tends normally to move the end 18 of the bar 17 into 85 a position that it will hold the check 19 in the seat 20 and prevent the check from being delivered from the carrier when the seat is inverted. The bar or rod 17 will assume this position when the container is empty. 90

When, however, the articles 23 are present in the container the lever 13 will be rocked about its pivot from the position shown in Figure 1 to the position shown in Figure 3, to withdraw the end 18 of the bar from beneath the check 19, thereby permitting the latter to drop upon a support 24, so that when the carrier 21 is then moved in one direction the check will be forced from the support 24 against a shiftable member 25 which releases 95 100

the check controlled mechanism and the check will drop from the support 24 into the machine.

The operation of the lever 13 is controlled by means of a pivotally mounted member 26 (see particularly Figure 5) which is supported by the wall of the container preferably by one end 27 of the member engaging in a suitable opening 28 in the container wall so that the member 26 will hang for free swinging movement.

The normal position of the portion 16 of the lever 13 is within the path of movement of the member 26.

When the container is empty and when the containers are rotated (in a manner not shown) it will be manifest that the member 26 will strike the portion 16 of the lever 13, but as there is no resistance to the member 26 it will spring backwardly into the container by its engagement with the portion 16 of the lever 13, thereby passing the lever 13 without rocking the latter about its pivot.

When, however, there are articles 23 in the container, as shown in Figure 2, the articles will hold the member 26 projected beyond the front of the container, with the result that when the container is then rotated the member 26 will be held against retraction and will engage the portion 16 of the lever 13 to rock the latter about its pivot 14 and thereby withdraw the extremity 18 of the rod 17 from beneath the check 19, thereby permitting the latter to drop into the machine.

A weight 29 is provided for the containers and this weight rests upon the articles 23, a portion of the front edge of the weight 29 adjacent the member 26 being cut away as at 30 so as not to interfere with the free swinging movement of the member 26 when the container is empty of articles and the weight assumes a position adjacent the lower portion of the member 26.

When the handle 31 which is connected with the carrier 21 is rotated and when the end 18 of the rod 17 is withdrawn to permit the check to be deposited in the machine, the shifting of the member 25 will release the check controlled mechanism to render a cam 32 operative. This cam during its rotation alternately engages projections 33 on a member 34 to rock the latter and the rocking of the member 34 will swing the lever 35 to actuate the ejector 36 in the manner as set forth in our co-pending application, and which constitutes no portion of the present invention.

As the check is delivered into the machine it will fall down a chute or passageway 37 and the check will be arrested in its movement into the chute by the rod 17.

The weight is also preferably provided with projections 38 which extend through the open front 39 of the container and cooperate with the sides of the opening in the front of

the container so as to insure the proper positioning of the weight 29 in the container.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. A vending machine including a shiftable container for the articles, ejecting means for the articles, a check chute, an element movable into the chute to arrest the movement of the check therethrough, an element connected with the first recited element for actuating the latter, a member carried by the container and adapted to be projected and maintained projected beyond the container by the articles in the container and to be moved into the container in the absence of articles therein, the said member when projected and held against retraction being adapted to engage and shift the second recited element to withdraw the first said element as the container is shifted.

2. A vending machine including a shiftable container for the articles to be vended, a check chute, a shiftable member arranged adjacent the path of movement of the container, an element connected with said member and movable into and out of the path of movement of the check through the said chute, and a freely shiftable member carried with the container and adapted to be maintained projected beyond the container by the articles in the container, whereby the last said member will engage and shift the first said member to retract the said element.

3. A vending machine including a shiftable container for the articles to be vended, a check chute, a shiftable member carried adjacent the path of movement of the container, means responsive to the movement of said member for controlling the movement of the check through the said chute, and a freely shiftable member carried with the container and adapted to be maintained projected beyond the container by the articles in the container, whereby the last said member will engage and shift the first said member to retract the said element.

4. A vending machine including a shiftable container for the articles to be vended, a shiftable member adapted to be projected into the path of movement of a check delivered into the mechanism and to be retracted, a member carried with the container, and means connected with the said shiftable member and having a projection normally arranged within the path of movement of the member that is carried by the container and adapted to be engaged by the last said member to shift the latter so that it will pass said projection when the container is empty, the

said member which is carried with the container being maintained projected by articles in the container to shift said projection to retract said shiftable member.

5 5. A vending machine including a shiftable container for the articles to be vended, a shiftable member adapted to be projected into the path of movement of a check in the mechanism and to be retracted, a pivotally mounted lever connected with said member, and a freely movable member carried with the container and adapted to be engaged by a portion of the lever and shifted thereby when no articles are in the container, the last said member being maintained against movement with respect to the container by articles in the container to cause it to engage and shift said lever to retract the first recited shiftable member.

10 6. A vending machine including a shiftable container, a member carried thereby for free shifting movement with respect thereto when the container is empty, said member being maintained projected and against retraction by articles in the container, a check chute, a member adapted to be projected across said chute and to be retracted, a shiftable member connected with the last said member for actuating it, a projection on the last said shiftable member, and means tending normally to position said projection in the path of movement of the shiftable member that is carried by the container whereby when said container is empty the said projection will engage and shift the member that is carried by the container and when articles are in the container the said projection will be shifted by the last said member.

15 7. A vending machine including a shiftable container for the articles to be vended, a check chute, means adjacent the path of movement of the container and operable to control the delivery of the check from said chute, and an element carried with the container and controlled by the articles in the container whereby the said element will be rendered active to actuate the said means to cause the check to be released, the said element being automatically rendered inactive

20 in the absence of articles in the container.

25 8. A vending machine including a shiftable container for the articles to be vended, a check chute, means adjacent the path of movement of the container and operable to control the delivery of the check from said chute, and an element carried with the container and controlled by the articles in the container whereby the said element will be rendered active to actuate the said means to cause the check to be released, the said element being shiftable with respect to the container by the said means in the absence of articles in the container to maintain the check from being released.

30 9. A vending machine embodying a shift-

able container for the articles to be vended whereby said container may be moved with respect to a delivery station, delivery mechanism for the articles, means for controlling the delivery of a check into the mechanism to render the delivery mechanism active, and means responsive to the movement of the said container as it arrives at the said delivery station with articles therein for rendering the check controlling means inactive to release the check, the last recited means being rendered inactive in the absence of articles in the container.

35 10. A vending machine embodying a shiftable container for the articles to be vended whereby said container may be moved with respect to a delivery station, delivery mechanism for the articles, means for controlling the delivery of a check into the mechanism to render the delivery mechanism active, and means responsive to the movement of the said container as it arrives at the said delivery station and controlled by the articles in the container for rendering the check controlling means inactive to release the check, the last said means being automatically rendered inactive in the absence of articles in the container.

40 In testimony whereof we have signed our names to this specification, on this 20th day of July, A. D. 1927.
